UNITED STATES PATENT OFFICE.

CHERI S. FREUND, OF CHICAGO, ILLINOIS, ASSIGNOR TO CONTINENTAL CEMENT TILE COMPANY, OF CHICAGO, ILLINOIS, A CORPORATION OF DELAWARE.

ROOF STRUCTURE.

Application filed November 3, 1921. Serial No. 512,410.

To all whom it may concern:

Be it known that I, CHERI S. FREUND, a citizen of the United States, residing at Chicago, in the county of Cook and State 5 of Illinois, have invented new and useful Improvements in Roof Structures, of which the following is a full, clear, concise, and exact description, reference being had to the accompanying drawing, forming a 10 part of this specification.

My invention relates to roof structures, and it has particular relation to structures of the character designated wherein light admitting members are positioned in the 15 roof and made a portion of the structure.

More particularly my invention contemplates the placing of slabs of corrugated glass in a roof structure in such manner that the entire roof will be water-tight. To 20 this end I position the tiles of the roof and the glass slabs in overlapping relation, and it is further an object of my invention to combine the opaque tiles and the transparent or translucent glass slabs in such a manner 25 that the edges of the slabs in each tier of the structure are so covered with a cap of tile or other material that the roof will be weatherproof, but will comprise relatively few parts.

30 In this connection I provide rolls to cover the adjacent edges of the slabs—both the tile and glass—in such a manner that the above desirable structure may be formed. To further promote the durability and 35 weather resisting qualities of my roof, I arrange the successive tiers of roofing members in progressively overlapping relation, and preferably cement the said overlapping edges together. Again, the adjacent edges 40 of the slabs in successive tiers are so positioned that they are staggered with respect to one another whereby the placing of the rolls which make the adjacent edges 45 water-proof is facilitated. In this connection I provide the tiles with recessed portions which are arranged to accommodate the rolls in the next tier of tiles and, in this way, insure that the overlapping edges will 50 be moisture-proof even at the points which have heretofore been the hardest to protect. Further, I provide particular tile supporting members at the overlapping edges of the 55 glass and tile slabs which facilitate the above described arrangement.

55 For a better understanding of my inven-

tion, reference may be had to the accompanying drawings, in which—

Figure 1 is an isometric view, partly in section, of a roof structure embodying my invention;

Fig. 2 is an isometric view of one of the tiles employed in the structure of Fig. 1;

Fig. 3 is an elevational sectional view taken on the line 3—3 of Fig. 1;

Fig. 4 is a plan view of a roof structure 65 analogous to that shown in Fig. 1, but wherein solid tiles alternate with glass slabs;

Fig. 5 is an elevational sectional view taken on the line 5—5 of Fig. 4;

Fig. 6 is a side elevational view taken on the line 6—6 of Fig. 3;

Fig. 7 is a view analogous to that of Fig. 6, but taken on the line 7—7 of Fig. 5;

Fig. 8 is a view analogous to that of Fig. 75 1, showing a modified roof structure embodying my invention;

Fig. 9 is a longitudinal section thru the roll in this last modified form of roof; and,

Fig. 10 is a detail view of a portion of the last mentioned roof.

Referring now more particularly to the structure shown in Fig. 1, trusses 11—11 have a plurality of purlins 12—12 laid at 85 right angles thereto, this structure comprising a foundation upon which the roof tiles are laid. The tiles 13—13 are provided with lips or feet 13^a, which extend over the edge of the upper purlin as shown, and 90 serve to support the tiles 13 when they are laid in a slanting position. A cap, formed of tiles 14—14, is placed at the peak of the roof. The tiles 13—13 are laid edge to edge and their adjacent edges are covered by 95 rolls 15—15 whereby a water-tight tier is comprised.

In Fig. 1 the next tier of roofing members comprises a plurality of corrugated glass slabs 16, the adjacent edges of these 100 slabs being covered by rolls 17. It will be noted that the rolls in the last mentioned tier are staggered with respect to the rolls 15 in the first described tier of tiles; that is, the junction of the edges of adjacent 105 members in the two tiers are so staggered. Each tile in the upper tier, however, is provided with a recessed semi-cylindrical portion 18 which extends over the rolls 17 in the next lower tier of roofing members. 110

The tiles 13 are cemented to the glass slabs, as shown, these all being in turn laid in cement on the purlins. The upper and lower ends of the glass slabs, however, rest 5 respectively upon and are cemented to specially formed tiles 19 19^a. The tiles 19^a have raised edge portions 20—20, and are provided with a rolled recess 21. At the upper edge of these tiles a foot 22 is provided which extends over the purlin and holds said special tiles in position to receive the glass slabs. The advantage of this form of construction is quite marked since it is in certain cases impracticable to provide 15 a supporting edge on the glass itself.

Extending between the two lowermost purlins is a tier of solid tiles 23—23, the latter being provided with lips 24 to secure them in place on the purlins, and it will 20 be noted that the adjacent edges of these tiles have rolls 25—25 overlying the junction of said edges. It will further be noted that the tiles 19^a are positioned between the lower edges of the glass slabs and the upper 25 edges of the tiles 23—23, and that the foot 22 secures these special tiles in this position, as shown. Moreover, the recessed semi-cylindrical portions 21 accommodate the upper ends of the rolls 25 whereby no 30 opportunity is afforded for moisture to work down under the edge-protecting roll.

The glass is cemented to these tiles 19^a and I find it desirable to provide holes 35 through the cement in the under corrugations in order that the moisture which condenses on the under side of the glass slabs may run down therethrough from the interior of the roof and be drawn off together with the moisture which is deposited 40 directly upon the upper surface of the roof.

The manner in which the adjacent edges of the corrugated glass slabs are protected is best shown in Fig. 3. A metal strip 26 45 may be laid over the junction of these edges on cement, and then cement is applied on the top of the metal strips after which the roll or cap 17 is laid down. In Fig. 3 it will be noted that the recessed semi-cylindrical portion 18 of the upper tile 13 extends 50 over and is cemented to the cap or roll 17. A longitudinal sectional view of the structure last described is shown in Fig. 6.

In Fig. 4 I have illustrated the manner in which the solid tiles and glass slabs may 55 be combined in the second tier of the roofing structure to eventuate a roof having alternate side-by-side glass and solid roofing slabs. The manner in which the adjacent edges of the dissimilar tile and of the glass 60 slabs are protected in order to make the structure water-proof is shown in Fig. 5. A metal filler 27 may be laid down between the edges of the two dissimilar materials and then over this and the edge of the slabs 65 cement is spread. The cap or roll 17 is

finally placed in position, as shown, and serves to adequately protect this point in the structure.

In describing the manner of placing the protecting rolls over the edges of the adjacent rolls I have referred to the use of metal strips or fillers but it is to be understood that these are not always necessary and, in fact, I frequently lay the cement directly on the junction and place the roll 75 thereover.

Referring now to Fig. 8, I illustrate a modified form of roofing structure wherein a different character of interposing member is used in place of the special tile 19^a. At 80 their upper edges the glass slabs are laid directly upon the purlin with only the interpositioning of a cord cushion 28 and at their lower ends they are cemented directly to the upper edge of the lower tier of tiles 23. 85 A flashing 29 extends under the glass and up over the rolls as best shown in Fig. 9. These glass slabs may be laid down in oakum instead of cement if such is desired. The positioning of the tiles as just described 90 eventuates a very desirable water-tight roof structure and is very quickly and easily constructed. Here, again, holes may be left in the cement at the lower edge of the glass slabs to permit the condensation on the 95 under surface of the glass slabs to run off.

While I have shown but three embodiments of my invention as utilized in a combined transparent and solid roofing structure, it is obvious that many modifications 100 therein may occur to those skilled in the art, and I desire, therefore, that my invention be limited only by the showing of the prior art and by the scope of the appended 105 claims.

What I now claim is new and desire to secure by Letters Patent of the United States is:

1. In a roof structure, supporting purlins, a plurality of opaque tile sections and transparent roof sections, some of the opaque sections overlying the transparent sections, and said transparent sections overlying others of said tile sections, and means extending under the transparent sections and 115 over the tile sections where said sections overlap.

2. In a roof structure, supporting purlins, a tier of tiles extending between certain of said purlins, supporting members 120 on said purlins, and transparent sections having their edges positioned between said supporting member and one edge of said tiles.

3. In a roof structure, supporting purlins, a tier of tiles extending between certain of said purlins, supporting members positioned on the lowermost of said last named purlins and having a toe extending there-over to hold them in position thereupon, and 130

transparent sections having their upper edges positioned on said supporting members, the lower edges of said first mentioned tiles resting upon the upper edges of said 5 transparent sections.

4. In a roof structure, supporting purlins, a tier of tiles extending between certain of said purlins, supporting members on said purlins, and transparent sections having 10 their edges positioned between said supporting member and one edge of said tiles, cap pieces covering the junctions of the tiles, and other cap pieces covering the junction of the transparent sections, said junctions being 15 staggered with respect to one another.

5. In a roof structure, supporting purlins, a tier of tiles extending between certain of said purlins, supporting members on said purlins, transparent sections having their 20 edges positioned between said supporting member and one edge of said tiles, cap pieces covering the junctions of the tiles, and other cap pieces covering the junction of the transparent sections, said junctions being staggered with respect to one another, and said 25 tiles being provided with roll portions which overlie the cap pieces covering the transparent section junctions.

6. In a roof structure, a plurality of purlins, a tier of tiles extending between certain purlins, a tier of alternate glass and tile sections extending between the next two purlins, a tier of tiles between the next two purlins, the lower edge of each tier resting on 30 top of the upper edge of the next lower tier, and toe pieces positioned on each of the purlins between which the glass sections extend, the upper toe piece resting directly on the purlin and the lower toe piece being 35 between the upper edge of a tile and the lower edge of the glass slabs.

7. In a roof structure, a plurality of purlins, a tier of tiles extending between certain purlins, a tier of alternate glass and tile sections extending between the next two purlins, a tier of tiles between the next two purlins, the lower edge of each tier resting on 40 top of the upper edge of the next lower tier, and toe pieces positioned on each of the purlins between which the glass sections extend, the upper toe piece resting directly on the purlin and the lower toe piece being 45 between the upper edge of a tile and the lower edge of the glass, said last named toe piece being recessed to accommodate a junc-

tion roll of the last named tier of tiles and being provided with junction edges which are in turn covered by a roll.

8. In a roof structure, a plurality of purlins, a tier of tiles extending between certain purlins, a tier of alternate glass and tile sections extending between the next two purlins, a tier of tiles between the next two purlins, the lower edge of each tier resting on top of the upper edge of the next lower tier, 60 toe pieces positioned on each of the purlins between which the glass sections extend, the upper toe piece resting directly on the purlin and the lower toe piece being between the upper edge of a tile and the lower edge of 65 the glass, junction rolls extending over the junctions of the glass sections of the second named tier, said last named toe piece being recessed to accommodate the junction roll of the last named tier of tiles and being provided with junction edges which are in turn covered by the rolls which cover the edge-to-edge junctions of the glass sections in the 70 second tier.

9. In a roof structure, a plurality of purlins, a tier of tiles extending between certain purlins, a tier of alternate glass and tile sections extending between the next two purlins, a tier of tiles between the next two purlins, the lower edge of each tier resting on 80 top of the upper edge of the next lower tier, the edge-to-edge junctions of the tiles being covered with a cap piece cemented thereover, the edge-to-edge junctions of a glass section and a tile section being first closed 85 with a metal filler and a cap piece being then cemented thereover, and toe pieces positioned on each of the purlins between which the glass sections extend, the upper toe piece resting directly on the purlin and the lower toe piece being between the upper edge 90 of a tile and the lower edge of the glass.

10. In a roof structure, a plurality of purlins, a tier of tile extending between certain purlins, a tier comprising corrugated glass 100 sections adjacent thereto, and cushioning means between the upper edge of the glass sections and a purlin, the lower edge of said tiles being cemented directly to the upper edge of the glass sections.

In witness whereof, I have hereunto subscribed my name.

CHERI S. FREUND.

Witness:

A. A. BRAND.
